(No Model.)

S. T. DUTTON.

INTERLOCKING APPARATUS FOR RAILWAY SIGNALING.

No. 503,530.

Patented Aug. 15, 1893.

UNITED STATES PATENT OFFICE.

SAMUEL TELFORD DUTTON, OF WORCESTER, ENGLAND.

INTERLOCKING APPARATUS FOR RAILWAY SIGNALING.

SPECIFICATION forming part of Letters Patent No. 503,530, dated August 15, 1893.

Application filed January 14, 1893. Serial No. 458,425. (No model.)

To all whom it may concern:

Be it known that I, SAMUEL TELFORD DUTTON, civil engineer, a subject of the Queen of Great Britain and Ireland, residing at Marl Bank, in the city and county of Worcester, England, have invented new and useful Improvements in Interlocking Apparatus for Railway Signaling, of which the following is a specification.

10 My invention relates to locking apparatus for railway points and signals, which I construct with a view to simplicity of parts and the reduction of friction in the gearing and also to shorten the draft upon the tappets.

15 In order that my invention may be better understood and more readily carried into effect I will proceed to describe the drawings hereunto annexed.

Figure 1 is a side elevation showing a lever 20 in its normal position, and the means by which the locking mechanism is operated. Fig. 2 is a front elevation of Fig. 1. Fig. 3 is a plan of the locking box or trough, showing the interlocking tappets, their notches, and the locks. Fig. 4 is an enlarged view of the fulcrum of the lever showing the slot in the projection beyond the fulcrum, in which the pin connecting the links to the tappet operates. Fig. 5 is a plan of Fig. 4.

30 The same letters refer to the same parts or substitutes therefor in the several figures of the drawings.

a is the main lever which may be a signal, point, point lock, or other operating lever for 35 signaling purposes.

b is the catch handle at the back of the lever *a*.

c is the rod connecting the catch handle to the drop box *d*.

40 *e* is the continuation of the catch rod below the segment of the locking frame.

f is the cross bar centered at *g* to the lever *a*, and connected at one end to the continuation *e* of the catch rod *c*. The other end of the 45 cross bar is connected to a pair of links *h*. The links *h* are connected in their turn by means of the pin *i* (which pin *i* moves in a slot *j*) to the pair of links *k*. The links *k* in their turn are connected to the interlocking tappet *l*.

50 *m* is the locking box or trough through which the tappets *l* move and in which the locking is effected; *n* is a lock in the locking trough.

l' is a notch in the tappet *l*. This is a locking notch. *l''* is a notch, also in the tappet *l*, but is a releasing notch. The lock *n* is shown 55 in the bottom of the locking trough; Fig. 3.

The operation of my invention is as follows: When the catch handle *b* is raised the cross bar *f* is so operated that a downward movement is given to the links *h*, the pin *i* is moved 60 to the bottom of the slot *j*, and the links *k* and the tappet *l* are thereby operated so that the locking of conflicting levers is effected. On referring to Fig. 3 it will be seen that the tappet *l* in the downward movement which it 65 takes presents a straight surface to the lock *n*; the notch *l'* having moved downward, thereby holding the lock *n* into the notch in the next tappet *l*, the lever connected to the tappet *l* is thereby locked. When now the movement of the lever *a* takes place, the projection *o*, being bolted about the fulcrum to the lever 70 *a*, is moved downward so that the links *k* are moved into the position that the pin *i* takes the position (in dotted lines, Fig. 4) of *p*; this 75 gives a very slight backward movement to the tappet *l*. It should be understood that in the first movement of the tappet by the raising of the catch handle the tappet *l* is moved some short distance beyond the required movement to effect the locking, so that 80 when the slight backward movement takes place, of the pin *i* assuming the position of *p* (dotted lines, Fig. 4), there is still latitude allowed for the perfect locking to have taken 85 place. On the catch handle being now replaced in the pulled over position of the lever a further forward movement is given to the tappet *l* by an upward movement of the pin *i* assuming the position *q* (in dotted lines 90 Fig. 4). This moves the tappet *l* sufficiently forward so that the release notch *l''*, as in Fig. 3, comes opposite a lock such as *r*, which lock would be connected to any lever which would be normally locked and should 95 be released by the forward movement of the tappet *l* connected to a lever such as *a*. The return motion of the lever *a* to its normal position is practically a reverse movement of the various parts until they assume their normal 100 positions as in Fig. 1. The slot *j* beyond the fulcrum is curved to a radius equal in length to the links *k*. The curve of the slot *j* regulates the progressive movement of the tappet

so that at any part of the stroke of the lever the rate of motion of the tappet b coincides with that of the catch rod c — e .

It is obvious that my invention is applicable to the ordinary lever and spring catch handle or to ordinary segmental plates with front and back notches, and to what is known as ordinary tappet locking.

Having fully described my invention, I wish it to be distinctly understood that I do not claim the principle of tappet locking generally, nor do I claim the principle of operating tappets by means of a catch rod; but,

What I do claim, and desire to secure by Letters Patent, is—

The combination, with a pivoted operating lever provided with a catch rod, of a crossbar pivotally connected to the said lever and

catch rod, a stationary locking box, a tappet sliding in the said box, the links h and k pivotally connecting the said tappet with the said crossbar, and the projection o on the operating lever provided with a slot adapted to guide the meeting ends of the said links, substantially as set forth.

In testimony whereof I hereunto affix my signature in the presence of two witnesses.

SAMUEL TELFORD DUTTON.
